UNITED STATES PATENT OFFICE.

GLEN I. COLBURN, OF GENEVA, NEW YORK.

NURSERY LABEL.

1,421,674.

Specification of Letters Patent. Patented July 4, 1922.

Application filed March 6, 1922. Serial No. 541,360.

To all whom it may concern:

Be it known that I, GLEN I. COLBURN, a citizen of the United States, residing at Geneva, in the county of Ontario and State 5 of New York, have invented certain new and useful Improvements in Nursery Labels, of which the following is a specification.

This invention relates to labels or tags, 10 particularly to those adapted for use by horticultural nurserymen, and has for its object the provision of a label or tag to be attached to trees, shrubs, or other plants and so constructed as to enclose directions 15 for planting and caring for the stock.

It is a well known fact that the ordinary 20 label or tag now in use by nurserymen in marking their trees, etc., consists merely of a small piece of wood having printed thereon 25 the name of the plant, and the purchaser of a plant so marked, unless an experienced grower, has nothing to guide him in planting. Furthermore, it is the common practice of nurserymen to guarantee that their 30 stock will live and the replacements they are forced to make on account of the non-growth of the stock are a considerable item, and are necessitated largely by improper planting. A separate circular of instructions 35 is not satisfactory, frequently inconvenient, and always liable to become confounded with other instructions.

It is with these facts in mind that the 40 present invention has been designed with the purpose of providing a tag which could be made conveniently of oiled paper, or other suitable material, attachable to a plant, and carry the name of the plant and planting instructions; the paper being folded and enclosing the instructions, while displaying the name.

With the object in view of providing such 45 a tag which will be very simple and inexpensive, and convenient in use, the invention consists in the construction and arrangement to be hereinafter more fully described and claimed and illustrated in the accompanying drawing, in which,

Figure 1 is a plan view of the tag ready 50 for use,

Fig. 2 a side elevation thereof,

Fig. 3 an end view,

Fig. 4 a plan view of the tag torn off and opened to display the instructions, and

Fig. 5 a plan view of the tag unfolded.

Referring more particularly to the drawing, the numeral 1 designates a sheet of suitable material, preferably oiled paper, provided at each end of its longitudinal axis with reinforced holes 2. On one side of the sheet is printed the name of the plant and a set of instructions 3 for planting. The sheet 1 is folded back on itself longitudinally along the lines 4 and 5, covering the instructions bearing side, and is then folded again transversely upon itself along the line 6. The flaps 7, 8, 9, and 10 will then all be disposed upon each other and will be upon the inside of the tag with the panels 11 and 12 forming the outside. The sheet 70 is perforated along the lines 13 and 14 so that when it is folded as described the tag will comprise the fixed portion 15 and the detachable portion 16. The name of the plant is printed transversely across the fixed 75 portion 15 of the panel 11 and longitudinally upon the detachable portion 16. The detachable portion further bears the legend "Tear off on dotted line. Planting directions inside."

The tag is attached to a plant as by a wire 17 passed through the holes 2 and twisted and then twisted about a stalk of the plant in the usual manner. The legend instructs the purchaser to tear the tag along 85 the dotted line. When this is done, the fixed portion 15, bearing the name of the plant still remains in place as identification, and the portion 16, torn off, upon being unfolded is seen to carry upon its reverse side full instructions for planting.

From the foregoing description and a study of the drawings it will be apparent that I have provided a tag enclosing instructions which is suitable for the use of 90 horticultural nurserymen and of any others experiencing the need of an article of this character, and which is simple, cheap, and highly efficient.

While I have shown and described the 100 preferred embodiment of my invention, it will of course be understood that I reserve the right to make such changes in the form, construction and arrangement of parts as will not depart from the spirit of the invention or the scope of the subjoined claims.

I claim:—

1. A tag comprising a sheet of material having its longitudinal sides folded inwardly, one side flat upon the central por- 110

- tion of the sheet and the other side upon the first side, the resultant strip being folded transversely at its center with its ends brought together, said end portions being provided with eyelets alining when said folding is completed, said sheet being perforated along transverse lines alining when said folding is completed whereby a portion thereof may be detached.
10. 2. A tag comprising a sheet of material perforated transversely adjacent its ends and bearing a legend on one side between said perforations and the longitudinal edges, said sheet having its sides folded inwardly upon the central portion of the

sheet to cover the legend thereon, the resultant strip being folded transversely at its center with the ends and said perforations alining respectively, and eyelets secured at the longitudinal centers of the ends of the sheet and alining when said sheet is folded, the other side of the sheet being provided between the lines of longitudinal folding with indicia and adjacent one eyelet with corresponding indica, the legend portion of the sheet being detachable.

In testimony whereof I hereto affix my signature.

GLEN I. COLEBURN.
